UNITED STATES PATENT OFFICE.

PETER MARTINUS LUND, OF BROOKLYN, NEW YORK.

CLOTHESLINE-SUPPORT.

1,330,082.

Specification of Letters Patent.

Patented Feb. 10, 1920.

Application filed September 5, 1919. Serial No. 321,835.

To all whom it may concern:

Be it known that I, PETER M. LUND, a citizen of the United States, residing at Brooklyn, in the county of Kings and State of New York, have invented certain new and useful Improvements in Clothesline-Supports, of which the following is a specification.

My invention relates to new and useful improvements in clothes line supports.

An important object of the invention is to provide a device of the above mentioned character by means of which the clothes may be placed upon the line from the interior of the house and the line subsequently secured exteriorly of the house, allowing the window, door or the like to be closed.

Other objects and advantages of the invention will be apparent during the course 20 of the following description.

In the accompanying drawings forming a part of this specification and in which like numerals are employed to designate like parts throughout the same,

25 Figure 1 is a perspective showing my device applied to a window,

Fig. 2 is a section taken on line 2—2 of Fig. 1,

Fig. 3 is a perspective showing the clamps 30 and supports for the clothes support,

Fig. 4 is a side elevation showing the clothes support applied, and

Fig. 5 is a perspective of the clothes line clamp.

35 Referring now more particularly to the drawings, the numeral 10 designates the sill of a window and the numeral 11, the side frame thereof. Secured to the side frame is a support designated as a whole by the 40 numeral 12.

The support 12 comprises a body portion 13, preferably round in cross-section, and having secured to one end thereof, a clamp member 14. The clamp member 14 may be 45 held in position upon the end of the body member by means of a rivet 15 or the like and the clamp member 14 is provided with an outwardly extending clamping foot 16. A coacting clamping foot 17 is provided, 50 having a tubular shank portion 18, which is slidably mounted upon the body member 13. The foot 17 is provided with an adjustable clamping screw 19, the inner face of which, being adapted to contact the woodwork, is 55 supplied with an enlarged portion 20. The clamping screw 19 may be provided with a

butterfly or the like for turning the same. A follower ring 21 is slidably mounted upon the body member 13 and is provided with a butterfly clamping screw 22, to secure the 60 ring in the desired position.

Formed in the inner end of the body member 13 is a slot 23, in which is pivotally mounted, as at 24, the angular extension of a lever 25. The angular extension of the 65 lever 25 is provided upon its end with a hook member 26, adapted to receive an eye 27 to which is secured a pulley block 28. This pulley block is adapted to receive the endless line 29. Means for securing the lever 25 in 70 position shown in Fig. 2, are provided, consisting of a ring member 25', which is adapted to be slipped over the end of the lever to secure it to the body member 13.

The side frame 11 of the window is provided upon the exterior thereof with a hook 30 or the like, adapted to receive the flexible attaching member 31 of a clamping member 32. The outer end of the flexible attaching member 21 is secured to the eye 33 or the 75 like, secured to one side of the clamping member 32. The clamping member 32 comprises plates 34 and 35, preferably formed of wood, joined together by clamping screws 36, provided upon their outer ends with butterfly nuts 37.

A clothes support 38 is provided, adapted to rest upon the sill 10 of the window. This clothes support is provided with upstanding edges 39 to retain the clothes and is flared 90 slightly at its outer end to prevent the clothes contacting with the window as they open, due to the movement of the line 29. The support 38 is provided upon its under face with a stationary clamping member 40, 95 adapted to engage one side of the sill and an adjustable clamping member 41, provided with a slot 42, adapted to receive a screw 43, provided with a butterfly nut 44. The adjustable clamping member 41 is provided upon its clamping face 45 with a butterfly screw 46, the inner end of which is provided with an enlargement 47, adapted to engage the woodwork of the sill 10.

As a majority of the weight of the clothes 105 will fall upon the inner end of the support 38, I have provided upon the under side of the inner end an adjustable supporting leg 48, hinged to the under side of the support, as at 49. The adjustable support leg 48 comprises a short leg 50, having secured thereto, as at 51, a band member 52, adapted to slid-

ably receive an extension leg 53. The extension leg may be secured in any desirable position by means of a clamping screw 54 or the like.

- 5 The operation of my device is as follows: The wet clothes are placed upon the support 38 and the line hung in the position shown in Fig. 2. The clothes are now placed upon the line and when the line is full, a 10 spacing ring 55 is placed about the lines, adjacent the clamping member 32. The clamps are then fastened about the line and the flexible attaching member 31 of the clamp placed upon the hook 30. I prefer that this 15 clamping member should comprise a portion of chain as this allows of considerable adjustment in the positioning of the clamp. The support 12 is now removed from the window, as is the clothes support 38, and 20 the line is allowed to hang with the pulley outside of the window, allowing the closing of the same.

It is to be understood that the form of 25 my invention herewith shown and described is to be taken as a preferred example of the same, and that various changes in the shape, size, and arrangement of parts may be resorted to without departing from the spirit 30 of my invention or the scope of the subjoined claims.

Having thus described my invention, I claim:

1. In a clothes line support adapted for use in windows and the like, removable 35 means for supporting the line interiorly of the window, comprising a support member provided upon one end with a stationary clamping foot, an adjustable clamping foot slidably mounted upon said support member, a follower ring for securing said adjustable foot in any desired position, and a pivoted lever provided upon one end with

means for releasably receiving one end of the line secured to the opposite end of said support member.

2. In a clothes line support adapted for use in windows and the like, removable means for supporting the lines interiorly of the window, comprising a support member provided upon one end with a stationary 50 foot extending at approximately right angles thereto, an adjustable foot slidably mounted upon said support member, a follower ring for securing said adjustable foot in any desired position, a clamping screw 55 carried by said adjustable foot, and a pivoted lever secured to the opposite end of said support member and provided upon one end with means for releasably receiving one end of the line.

3. In a clothes line support adapted for use in windows and the like, removable means for supporting the line interiorly of the window, comprising a support member, adjustable means for securing said support 65 member to the frame of the window, a pivoted lever carried by said support member, and provided upon one end with means for releasably receiving one end of the line, the other end of said pivoted lever being angularly disposed and lying against said support member when the lever is in position to receive the line, and a ring slidably mounted upon said support member and adapted to engage the angular disposed end 70 of said lever to secure said lever in the supporting position.

In testimony whereof I affix my signature in presence of two witnesses.

PETER MARTHINUS LUND.
